UNITED STATES PATENT OFFICE.

HERBERT S. THOMPSON, OF PEEKSKILL, NEW YORK, ASSIGNOR TO THE STANDARD TEXTILE PRODUCTS COMPANY, OF YOUNGSTOWN, OHIO, A CORPORATION OF OHIO.

CONVERTIBLE AND PORTABLE TOP.

1,375,027.

Specification of Letters Patent. Patented Apr. 19, 1921.

Application filed September 3, 1920. Serial No. 407,896.

To all whom it may concern:

Be it known that I, HERBERT S. THOMPSON, a citizen of the United States, and a resident of Peekskill, county of Westchester, 5 and State of New York, have invented certain new and useful Improvements in Convertible and Portable Tops, of which the following is a specification.

This invention relates to apparatus for 10 converting an open carrier such as a railway car into a closed carrier. An object of the invention is to provide an apparatus for this purpose which may be readily applied to a railway car or other carrier and which at 15 the same time may be taken down so as to provide an open car should a closed car not be necessary. In some parts of the country it is necessary under present conditions to transport material such as coal for example 20 long distances in open cars, with the result that after the cars have been unloaded it is necessary to return the cars empty to the mines whereas with the present apparatus, after the cars have been unloaded, they can 25 be readily converted into closed cars and loaded with perishable goods which may be sent back to the mines or any other part of the country desired.

Briefly, the apparatus of the present invention 30 comprises a portable framework adapted to be removably secured to an open carrier such as a gondola car, which framework when in place constitutes a supporting frame for a canopy, such as a canvas or tarpaulin, which can be thrown over the framework and fastened to the sides or end of the car or other carrier so as to convert the same 35 into a closed carrier.

In the accompanying drawings wherein 40 an embodiment of this invention has been illustrated—

Figure 1 shows in part sectional elevation a railway car with the present improved apparatus applied thereto;

Fig. 2 is a section taken on the line 2—2 of Fig. 1;

Fig. 3 is a plan view of the apparatus of Fig. 1;

Fig. 4 is a sectional view showing one of 50 the roof members folded down in place in the position that the roof members assume when the apparatus is not in use; and

Fig. 5 is an enlarged view of the ends of the roof members showing the interlocking

feature thereof which will be referred to in detail later on.

Referring now to the drawings in detail, 1 designates a gondola car having sides 3 and bottom 4, the car being supported on wheels 5 on a track 6. This car or carrier 10 may be of any of the many well known types of open top railway cars. Removably secured to the sides 3 of this car are side members or stakes 7, these side members or stakes being received by members 8 secured to the 15 inner side or outer side of the side members 3 of the car. The side members 7 are adjustable in the members 8 vertically with respect to the car and are held in adjusted position by spring pressed pins 9 adapted to 20 engage notches 10 provided for that purpose in the stakes or side members 7. This construction is plainly shown in Fig. 1.

The side members 7 have pivotally secured to them roof members 11 and 12. 25 These members are preferably made of metal tubing for lightness of construction, and the members 11 extend longitudinally while the members 12 extend transversely of the car 1. The members 11 are secured to 30 the side members 7 in any suitable manner so long as the same may be pivoted relatively to the side members while the members 11 and 12 are secured to each other by threaded couplings 13. From Figs. 1 and 2, it will be 35 seen that the members 11 and 12 just referred to, constitute a frame at each side of the car and by reason of the fact that these members are pivoted to the side members or stakes 7 the roof members 11 and 12 may be 40 collapsed as shown in Fig. 4 or may be moved to the position shown in Fig. 2 to form a support for a canopy 14. From Fig. 45 2, it will be seen that the roof members, have an interlocking connection, the members 12 at one side of the car being provided with a member 15 having a cut out portion 16 which is adapted to receive the end of the 50 opposed roof members thereby forming a lock for the roof members to prevent collapse of the same. The roof members furthermore it will be noticed when in locked position are in the form of an arch in order to strengthen the roof structure. The 55 roof member or members carrying the locking member 15 also have secured to them a runway 17 extending lengthwise of the car.

When the device is in operation it will be

seen that the roof members are moved to the position shown in Fig. 2 with their ends interlocking and with the runway 17 in place. The tarpaulin or canvas cover 14 is 5 then thrown over the car being supported by the roof members so far as the upper part of the car is concerned, the sides of the cover being brought down over the sides and ends of the car and fastened in any suitable manner, as shown at 18. With the parts in this 10 position it will be apparent that an open car has been converted into a closed one. In addition to the parts already referred to I may provide, if desired, a wire netting 19 15 between or filling up the spaces between the members 11 and 12 so that unauthorized removal of goods from the car is prevented, the members 11 being locked in their interlocked position by chain and padlock 20 20 and 21.

If it be desired to use the car as an open carrier the tarpaulin or canvas cover 14 may be removed, the roof members unlocked and merely dropped down to the position 25 shown in Fig. 4 for example on the inner side of the car.

While I have shown the roof members 11 and 12 formed of tubing it is to be understood that the same may be made of any 30 other suitable material, tubing merely having been shown for purposes of illustration. It is to be understood also that changes may be made in the details of construction described and illustrated within the scope of 35 the present invention.

The roof members herein described are made in sections as will appear from the drawings, particularly with respect to their length. This is done for the reason that if 40 it be desired to apply the top to a longer car another section may readily be added thereby avoiding the necessity of providing roof members of different lengths for various length cars.

45 What I claim is:

1. A portable top for a carrier, comprising side members removably secured to the carrier, roof members pivotally secured to said side members, said roof members interlocking to sustain the same in the form of 50 an arched top or roof for the carrier, and a member secured to certain of said roof members to constitute a walk or runway for the top.

55 2. A portable top for a carrier, comprising

side members removably secured to the carrier, interlocking roof members pivotally secured to the said side members, a runway secured to the roof members, and a removable cover supported by said roof members 60 and secured to said carrier.

3. In apparatus for converting an open carrier into a closed carrier, the combination of adjustable side members, means for securing the same to the carrier, means for holding the side members in adjusted position, frames pivotally secured to said side members and having interlocking portions to sustain the roof members in the form of an arch above the carrier, a runway secured 70 to the roof members, and an imperforate removable cover supported by the roof members and secured to the carrier.

4. In apparatus for converting an open carrier into a closed carrier, the combination of adjustable side members, means for securing the same to the carrier, means for holding the side members in adjusted position, frames pivotally secured to said side members and having interlocking portions 80 for sustaining the roof members in the form of an arch above the carrier, and an imperforate removable cover supported by the roof members and secured to the carrier.

5. In apparatus for converting an open 85 carrier into a closed carrier, the combination of adjustable side members, means for securing the same to the carrier, means for holding the side members in adjusted position relatively to the carrier, and frames pivotally secured to said side members and having interlocking portions sustaining the roof members in the form of an arch above the carrier.

6. In apparatus for converting an open 95 carrier into a closed carrier, the combination of adjustable side members, means for securing the same to the carrier, means for holding the side members in adjusted position, sectional frames pivotally secured to 100 said side members and having interlocking portions sustaining roof members in the form of an arch above the carrier, a runway secured to the roof members, and a removable imperforate cover supported by the roof 105 members and secured to the carrier.

This specification signed this 23 day of August, 1920.

HERBERT S. THOMPSON.
